UNITED STATES PATENT OFFICE.

ISAAC E. PHELPS, OF WAHOO, NEBRASKA.

FILING-CASE.

1,325,041.

Specification of Letters Patent. Patented Dec. 16, 1919.

Application filed January 8, 1919. Serial No. 270,193.

To all whom it may concern:

Be it known that I, ISAAC E. PHELPS, a citizen of the United States, residing at Wahoo, in the county of Saunders and State 5 of Nebraska, have invented certain new and useful Improvements in Filing-Cases, of which the following is a specification, reference being had to the accompanying drawings.

10 This invention relates to certain improvements in filing cases, and it is an object of the invention to provide a device of this general character constructed in a manner whereby parcels such as envelops, papers, 15 or the like may be readily inserted therein so that the same may be filed or stored with convenience and facility.

It is also an object of the invention to provide a novel and improved device of this 20 general character which serves to effectively protect the articles placed therein, and which particularly serves to prevent the contents of the case from becoming dust-laden.

It is also an object of the invention to provide a novel and improved case of this general character provided with a hinged lid or covering, wherein said lid or cover is connected with the body of the case in a manner whereby the lid or cover when in 30 open position affords no obstruction or hindrance to the insertion of the articles within the case.

The invention consists in the details of construction and in the combination and 35 arrangement of the several parts of my improved filing case whereby certain important advantages are attained and the device rendered simpler, less expensive and otherwise more convenient and advantageous for 40 use, as will be hereinafter more fully set forth.

The novel features of my invention will hereinafter be definitely claimed.

In order that my invention may be the 45 better understood, I will now proceed to describe the same with reference to the accompanying drawings, wherein:

Figure 1 is a view in perspective of a filing case constructed in accordance with an 50 embodiment of my invention with the lid or cover in open position;

Fig. 2 is a fragmentary, longitudinal transverse sectional view taken through the case, as illustrated in Fig. 1;

55 Fig. 3 is a fragmentary, longitudinal, transverse, sectional view taken through a

case constructed in accordance with a further embodiment of my invention, with the lid or cover in closed position;

Fig. 4 is a view in perspective of a case 60 constructed in accordance with another modification, the lid or cover being in open position;

Fig. 5 is a fragmentary, longitudinal transverse, sectional view taken through the 65 device as illustrated in Fig. 4, with the lid or cover in closed position; and

Fig. 6 is a fragmentary, longitudinal, transverse, sectional view taken in accordance with a still further embodiment of my 70 invention, the lid or cover being also shown in closed position.

As is particularly illustrated in the accompanying drawings, C denotes a container or body constructed in accordance 75 with an embodiment of my invention, and which is preferably rectangular in form with one end open and the front face 1 of the case or body C terminates a predetermined distance inwardly of the free end of 80 the rear face or wall 2, and which arrangement provides a means whereby the insertion of papers, envelops or the like within the case or body C is materially facilitated. The end portion of one of the side walls 85 3 of the casing or body C intermediate the outer or free ends of the faces or walls 1 and 2 has its outer extremity rounded, as indicated at 4 in a direction toward the rear face or wall 2, while the corresponding portion 90 of the second side wall 3 has its outer edge disposed on substantially a sigmoidal line as indicated at 5. This structure also results in a more convenient insertion of the articles within the casing or body C. It will 95 be understood, however, that if preferred, these portions of the side walls 3 may be of similar construction, but it is not thought that a particular illustration is necessary, as the arrangement illustrated in Fig. 1 is preferred.

L denotes a lid or cover member comprising a back plate 6 of a length substantially equal to the width of the casing or body C, and the lower or inner marginal portion of 105 the plate 6 is hingedly connected as at 7 with the outer surface of the rear wall or face 2, and preferably through the medium of a flexible strip. The ends of the plate 6 are provided with the inwardly directed walls 110 or flanges 8, which are adapted to overlie the free end portions of the side walls 3. The

outer or upper longitudinal marginal portion of the plate 6 is defined by the inwardly directed flange 9 with which the outer ends of the flanges 8 are rigidly connected. The 5 flange 9 is of a width substantially equal to the major thickness of the casing or body C, and the outer longitudinal marginal portion of said flange 9 has hingedly engaged therewith a flap 10 which is adapted to overlie the 10 front face or wall 1 so that when the lid or cover is in closed position the contents of the body or casing C are effectively protected and particularly against dust. The flap 10 is also provided at its outer or free 15 longitudinal, marginal portion with a tongue 11 which is adapted to be inserted through a slot 12 produced in the outer face or wall 1 of the body or casing C so that the lid or cover L will be maintained in closed position.

20 In the form of my invention illustrated in Fig. 3, the structural features are substantially the same as has been just recited relative to the embodiment of my invention disclosed in Figs. 1 and 2, except that the plate 25 6' of the lid or cover member 1' is hingedly connected through the medium of a flexible strip 7' or the like to the outer surface of the front face or wall 1' of the casing or body C'. The flap 10' is provided with a tongue 30 11' insertible through an opening 12' produced in the rear face or wall 2'.

In the form of my invention particularly illustrated in Figs. 4 and 5, the casing or body C^a is substantially the same form of 35 construction as has hereinbefore been recited relative to the casing or body C and the lid L^a is also substantially the same construction and configuration as the lid or cover L with the exception that the flap or 40 front face 10^a thereof has its end marginal portions rigidly secured to the outer longitudinal marginal portions of the side flanges 8'.

The flap or plate 10^a is also provided with 45 a tongue 11^a which is adapted to be inserted in the slot 12^a produced in the front face or wall 1^a of the casing or body C^a.

The form of my invention illustrated in Fig. 6 is substantially the same as disclosed 50 in Figs. 1 and 2 with the exception that the upper or outer ends of the faces or walls 1^b and 2^b of the casing or body C^b are substantially flush and provided with the cut out portions 14 to facilitate the insertion of the 55 papers or the like within the casing or body C^b. The lid or cover L^b is substantially the same as the lid or cover L^a except that the

plate 10^b extends beyond the outer or free ends of the faces 1^b and 2^b when the lid or cover L^b is in closed position, and which 60 construction is required in order to permit the lid or cover L^b to have the desired free and unobstructed swinging movement to adjust the same into either open or closed position.

65 From the foregoing description, it is thought to be obvious that a filing case constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not 70 75 wish to be understood as limiting myself to the precise arrangement and formation of the several parts herein shown in carrying out my invention in practice except as hereinafter claimed.

80 I claim:

1. A device of the character described comprising a casing having one end open, and a cover for the open end of the casing hingedly connected to a wall of the casing 85 below the open end thereof, a face wall of the casing having its outer end terminating inwardly of the outer end of the second face wall, the side walls of the casing extending to the outer end of the second face wall, 90 the outer end of one of said side walls being sigmoidal in form.

2. A device of the character described comprising a case having one end open, and a lid coacting with the open end of said case, 95 said lid comprising a rear plate hingedly connected with a face wall of the casing inwardly of the open end of said casing, end flanges carried by said plate, a second plate secured to the first named plate and the end 100 flanges, a third plate secured to the second named plate and the end flanges and adapted to overlie the second face wall of the casing when the lid is in closed position, said third plate of the lid being provided with a 105 tongue, the second face wall of the casing being provided with a slot through which the tongue is insertible.

In testimony whereof I hereunto affix my signature in the presence of two witnesses. 110

ISAAC E. PHELPS.

Witnesses:

OSCAR HANSON,
CHAS. TERRY.
